(57) **CLAIM**

The ornamental design for a cake container, as shown and described.

DESCRIPTION

FIG. 1 is a top, front, right side perspective view of a cake container, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an exploded top, front, right side perspective view thereof.

The broken lines in the drawings depict portions of the cake container that form no part of the claimed design.
